UNITED STATES PATENT OFFICE.

SAMUEL D. RUTH, OF BEATRICE, NEBRASKA.

PAPER CUTTING AND FOLDING MACHINE.

SPECIFICATION forming part of Letters Patent No. 731,624, dated June 23, 1903.

Application filed October 1, 1902. Serial No. 125,551. (No model.)

To all whom it may concern:

Be it known that I, SAMUEL D. RUTH, a citizen of the United States, residing at Beatrice, in the county of Gage and State of Nebraska, have invented a new and useful Paper Cutting and Folding Machine, of which the following is a specification.

The object of the present invention is to provide a machine or apparatus for slitting and folding sheets of paper, envelopes, and the like for the purpose of forming a fastening or securing device to hold a number of sheets of paper together or to form a closure for an envelop.

A further object of the invention is to construct a device of this character in which the operations of slitting, folding, and interlocking the folded portion may be carried on in sequence with a single movement of an operating jaw or lever.

With these and other objects in view the invention consists in the novel construction and arrangement of parts hereinafter described, illustrated in the accompanying drawings, and particularly pointed out in the appended claims, it being understood that various changes in the form, proportions, size, and minor details of the structure may be made without departing from the spirit or 30 sacrificing any of the advantages of the invention.

In the accompanying drawings, Figure 1 is a longitudinal sectional elevation of a paper cutting and folding machine constructed in accordance with my invention. Fig. 2 is a plan view of the device, the upper lever or jaw being broken away and shown partly in section. Fig. 3 is a transverse sectional elevation of a portion of the folding and cutting mechanisms on the line 3-3 of Fig. 1. Fig. 4 is a detail perspective view of the folding devices detached from the machine. Fig. 5 is a similar view of a pair of knives which are employed for cutting the interlocking incisions. Fig. 6 is a longitudinal sectional elevation of the machine, illustrating a modified construction. Fig. 7 is a transverse sectional elevation of the same on the line 7-7 of Fig. 6. Figs. 8, 9, and 10 are detail perspective views illustrating the various steps in the cutting and folding of the paper.

Similar numerals of reference are employed to indicate corresponding parts throughout the several figures of the drawings.

The apparatus forming the subject of the present invention is designed more especially as an improvement on the device illustrated and described in an application for United States Letters Patent filed by me on July 17, 1902, under Serial No. 116,010.

Referring to the drawings, 10 indicates a suitable bed-plate, in the upper surface of which are formed a pair of parallel slots 11 to receive and guide a pair of stop-pins 12, said pins being connected by rods 13 to a cross-bar 14 at the front end of the base. The central portion of the cross-bar 14 is provided with a screw 15, having an operating-knob 16, said screw extending into a threaded opening in the end of the base to permit the adjustment of the pins either toward or from the front end of said base. Arranged centrally of the base is a slightly-elevated plate 17, disposed midway between the two stop-pins 12 and having at its front end a pair of convergent cutting edges 18, arranged at angles at which it may be desired to form the incisions in the paper or envelop. Near the rear portion of each of the cutting edges 18 is pivoted a cutting-knife 19, which is connected by a link 20 to one side of an operating-lever 21, the latter being pivoted at the rear end of the base-plate and provided with a suitable handle 22. This operating-lever is normally held in the elevated position illustrated in Fig. 1 by tension-springs 23, extending between a fixed eye on the base and a hook carried by the lever. The central portion of the plate 17 is recessed or grooved for its entire length and serves to receive and guide a folding-strip 25, movable longitudinally of the plate 17 and serving to engage and bend the paper tongue from the position illustrated in Fig. 8 to that shown in Fig. 9. The folding strip is less in thickness than the plate 17 in order that it may the better engage and move the paper tongue beyond the cutters, and said strip is provided with slots 26, through which extend guiding-pins 27, carried by the base and serving to prevent excessive upward movement of the strip during the folding operation, said pins being of

60

sufficient length to permit a slight upward movement of the strip, as may be required during the folding operation and to allow the device to accommodate itself to varying thicknesses of material.

At a point under the rear portion of the operating-lever is a standard 30, carried by the base and serving as a support for the central pivot-pin 31 of a bell-crank lever 32, the vertical arm of which is fitted in a recess in the rear end of the folding-strip and the horizontal arm being adapted for operative contact with a block 33 on the under side of the operating-lever. This block is yielding, being formed of rubber or provided with a yielding cushion which will permit a downward movement of the operating-lever after the folding-strip has completed its work.

Projecting from the opposite sides of the lever 21 are lugs 35, carrying compression-springs 36, the latter being provided at their lower ends with plates 37, adapted for contact with the paper or envelop after the insertion of the latter between the bed-plate 25 and lever and in advance of the cutting operation of the knives 19, the springs being of sufficient length to permit free downward movement of the operating-lever to accomplish the several operations.

The base is recessed for the reception of a block 39, which may be adjusted toward and from the cutting-knives 19 by means of the screw 40, extending through a threaded opening in the base. This block carries two angular knives 41, which are preferably parallel with each other and are adapted to form incisions or slits 42 in the sheet of paper for the reception of the inclined sides of the tongue cut by the knives 19, and to facilitate the entrance of the sides of the tongue into said incisions each of the knives is recessed, as indicated at 43. At points between the outer sides of the knives and the adjacent edges of the block the surface of the block is slightly raised, as indicated at 44, and the holding-plates 37 are arranged in alignment with these elevated portions and are adapted to force the paper or envelop down against the block and assist in the formation of the incisions 42 in the paper.

At a point between the two compression-springs 36 the operating-lever is provided with a depending block 49, adapted for contact with the paper tongue after the preliminary-folding strip 25 has completed its work. On each side of the block 49 are two or more guiding-pins or screws 50, forming guides for a slotted folding-plate 51, each plate being normally depressed by a small spring 52 and being adapted to come into contact with the side portions of the paper tongue immediately after the latter is partly bent over by the folding-strip 25, and the lower edge of each plate is recessed, as indicated at 53, to permit the passage of the sides of the tongue through the incisions 42. On the front of the block is mounted a vertically-movable

bar 54, normally depressed by a spring 55 and serving as a guide for an inclined finger or lug 56, carried by a spring 57 on the rear face of the bar 54.

The operation of the device is as follows: After adjusting the pins 12 to the desired position the folded paper or the envelop is inserted under the spring-plates 37 until the edge of the paper rests against the stop-pins, said stop-pins determining the length of the inclined slits or incisions formed in the paper. The operating-lever is then depressed, and the spring-pressed plates 37 come into contact with the paper on the outer sides of the knives 41, and at the same time the lower end of the bar 54 and the lower face of the inclined tongue or finger 56 come into contact with the paper at a point between the two knives 41. These devices, together with the knives, form cutting-dies, the knives being forced through the paper, while the central portion of the paper between the two knives is forced down below the paper in contact with the elevated portions 44 of the block 39. As the downward movement of the lever 21 is continued the knives 19 are forced past the stationary cutting edges 18 and the inclined incisions are formed, the body of the paper being pressed down into contact with the upper surface of the base, while the tongue remains on the slightly-elevated plate in convenient position to be engaged by the subsequent movement of the folding-strip. The downward movement of the levers continuing, block 33 engages the horizontal arm and bell-crank lever 32 and effects a forward movement of the folding-strip, the wedge-like paper tongue being forced over to a position above the finger or lug 56 and immediately under the block 49, which has not yet reached operative position. As the paper tongue is resting on the finger or lug 56 the folding-plates 51 engage the side portions of the tongue and fold the latter downwardly, the tongue being slightly bent or buckled over the finger 56 and assuming the shape shown in Fig. 9. Further downward movement of the lever then brings the lower end of the block 49 into engagement with the central portion of the paper tongue and forces the same downward and owing to the inclination of the upper face of the finger 56 forces the latter through the guided slot of the bar 54. The sides of the tongue then pass through the recesses 53 of the plates 51 and enter the recessed portions 42 of the knives 41, the entire operation being completed when the block 49 has firmly pressed the paper against that portion of the block 39 between the two knives 41. The lever is then allowed to resume its elevated position under the influence of the spring 23, and the paper or envelop is removed from the knives 41, the edge portions of the tongue, which are projected beyond the vertical planes of said knives, bending to an extent sufficient to permit the withdrawal of the paper from the knives and

leaving the wedge-like tongue firmly interlocked in the parallel incisions, as illustrated in Fig. 10.

In some cases it may be desired to employ a larger or more powerful machine for cutting through thicker paper or a large number of sheets or layers of paper, and for this purpose I may employ a device such as illustrated in Figs. 6 and 7. In this case the structure and operation are practically the same as that previously described, but the various movable members are actuated in sequence by a plurality of cams carried by a sliding frame or plate. The block 49' is provided with an upper stem 60, which is guided in a suitable opening formed in the upper portion of a frame 61, the block being maintained in elevated position by a tension-spring 62 and provided at its upper end with an antifriction-roller 63, which is held against a cam 64, carried by a plate or frame 65, which is adapted to guideways on the upper portion of the main supporting-frame. The block carries the side plates 51', corresponding in construction and operation to the side plates 51. (Shown in Figs. 3 and 4.) On the front face of the bar 49' is guided a bar 54', having at its lower end a finger 56' to be forced backward on the descent of the block 49' in the manner previously described. The two presser-plates 37' are operatively connected through the springs 36' to brackets 69, carried by cutting-knives 70, adapted to coöperate with the knives 41 in the formation of the parallel slots or incisions, and the knives 70 are both connected to a vertically-guided bar 71, having at its upper end an antifriction-roller 72, adapted to engage a cam 73, carried by the sliding frame 65. The main cutting-knives for the formation of the wedge-shaped tongue are operatively connected to a vertically-movable bar 74, having at its upper end an antifriction-roller 75, adapted for engagement with a cam-bar 76, carried by the frame 65, and in similar manner the bell-crank lever of the folding tongue is connected to a vertically-movable rod 77, carrying at its upper end an antifriction-roller 78, adapted to engage a cam-bar 79. The frame 65 is provided with rack 80, intermeshing with a gear-segment 81, carried by a transversely-disposed shaft 82, having an operating-handle 83, and normally the frame is maintained in initial position by a suitable tension-spring 84. In the operation of the mechanism shown in Figs. 6 and 7 the paper to be secured together is introduced below the movable cutting-knives and the gear-segment is partly rotated by means of the crank operating-handle 83. The first effect of the forward movement will be to cause the depression of the two spring holding-plates 37' into contact with the paper, the cam 73 effecting this movement. The cam 76 will then depress the rod 74 and move the pivoted cutting-knives to operative position for the formation of the tongue in the paper. The anti-

friction-roller 72 is then again depressed through the action of the cam 73, and the cutting-knives 70 act to form the parallel slits 70 or incisions and immediately thereafter are allowed to return to normal position, while the plates 37' are still held in contact with the paper. After this movement the cam 64 acts on the antifriction-roller 63 to depress 75 the block 49' until the finger 56' comes into contact with the paper. Immediately after this movement the cam 79 depresses the antifriction-roller 78 and forces the tongue-folding slide forward until the wedge-shaped 80 tongue of paper rests on top of the finger 56'. Continued movement of the frame 65 next brings the cam 64 into position to again depress the roller 63 and block 49', the folding-plates 51' engaging with the sides of the paper tongue and bending the same to the position shown in Fig. 9, after which the further descent of the block 49' forces the edges of the tongue through the parallel incisions in the paper and moves the finger 56' to the rear. When released, the parts are returned to normal position by one or more tension-springs 84.

The device forms a simple and convenient means of securing paper and envelopes without the expense of eyelets, paper-fasteners, or similar securing devices and is of especial value for fastening sample-envelopes or circulars in such manner as to protect the contents of the envelop and at the same time 95 permit the ready opening of the same for inspection by the postal authorities, as required in some classes of mail.

Having thus described my invention, what I claim is—

1. In combination, means for cutting paper to form a tongue and to form a pair of tongue-receiving incisions, and means for folding said tongue and forcing the opposite sides thereof through said incisions.

2. In combination, means for cutting paper to form a tongue and for forming tongue-receiving incisions, means for folding the tongue, and a movable operating device adapted to successively operate the cutting and folding 110 means and to force the tongue through said incisions.

3. In combination, cutting-knives for forming a tongue, knives for forming tongue-receiving incisions, means for folding the tongue 120 and forcing the same through the incisions, and an operating-lever for effecting the cutting of the paper, and the folding and interlocking of the tongue by a single movement.

4. In a device of the class specified, a base-plate having knives adapted to form incisions in the paper, means for cutting a tongue in said paper, an operating-lever, a block depending from the lever, an inclined finger or lug supported by the block and adapted to be moved to inoperative position by said block, means for folding the paper tongue to a position under the block, and yieldable

folding-plates carried by said block and adapted to engage side portions of the tongue and fold the latter over said inclined fingers.

5. In a device of the class described, means for cutting paper to form a tongue, a pair of inclined knives having lower recessed portions, a block carrying said knives, that portion of the block between the knives being arranged in a horizontal plane below that portion of the block outside the knives, a lever, spring-pressed plates adapted to engage the paper and force the same into contact with the elevated portions of the block, a block depending from the lever, a vertically-yieldable bar and a pair of folding-plates carried by said depending block, a yielding finger or lug carried by said bar and adapted to engage with the central portion of the paper tongue, means for folding the paper tongue into contact with said finger.
6. In a device of the class described, cutting-knives for forming a tongue in a paper

sheet or envelop, auxiliary knives for forming tongue-receiving incisions, means for engaging the central portion of the tongue between said incisions and for bending said tongue lengthwise, and means for flattening the tongue and forcing the inclined edges thereof through said incisions.

7. In combination, cutting-knives for forming a tongue, cutting-knives for forming tongue-receiving incisions, means for folding the tongue and forcing the opposite edges thereof through said incisions, a supporting-frame, and a reciprocating cam-carrying frame for engaging and operating the several cutting and folding mechanisms.

In testimony that I claim the foregoing as my own I have hereto affixed my signature in the presence of two witnesses.

SAMUEL D. RUTH.
